ATTORNEY

UNITED STATES PATENT OFFICE.

PAUL J. WEBER, OF KANSAS CITY, MISSOURI, ASSIGNOR OF ONE-HALF TO SIDNEY S. MAY, OF ST. LOUIS, MISSOURI.

AUXILIARY AIR-INLET DEVICE FOR INTERNAL-COMBUSTION ENGINES.

1,420,615.

Specification of Letters Patent. Patented June 20, 1922.

Application filed December 20, 1917, Serial No. 208,144. Renewed April 27, 1922. Serial No. 557,032.

To all whom it may concern:

Be it known that I, PAUL J. WEBER, a citizen of the United States, residing at Kansas City, in the county of Jackson and State of Missouri, have invented certain new and useful Improvements in an Auxiliary Air-Inlet Device for Internal-Combustion Engines, of which the following is a specification.

10 This invention relates to attachments for gasoline motors and the primary object is to provide a device for supplying hot air to the explosive charge as it is emitted from the carbureter so that the mixture will be taken 15 into the cylinders at a higher temperature than would otherwise be the case.

One object of the invention is to provide an attachment of this character that will utilize the heat generated by the exhaust 20 and passing through the exhaust manifold of the motor, to mix with the explosive charge as it is ejected from the carbureter, so that the charge when it enters the cylinder will have a higher coefficient of combustion. The invention also aims at the 25 provision of an attachment of this character that may be readily interposed between the carbureter and the manifold of the ordinary gasoline motor and which will be 30 provided with means whereby the exhaust gases from the manifold may be utilized, the same being strained and filtered before they pass into the intake manifold.

In the drawings,—
35 Figure 1 is a side elevation of a gasoline motor showing my attachment applied thereto.

Figure 2 is a fragmentary section through 40 the attachment showing the connecting portions of the intake manifold and the carbureter.

Figure 3 is a section taken on the line 3—3 of Figure 2 and Figure 4 is a section taken 45 on the line 4—4 of Figure 1.

By referring to the drawings it will be seen that the motor A is provided with the usual intake manifold B and the exhaust manifold C the latter being provided with the discharge pipe which leads to the muffler, 50 not shown, beneath the car. The carbureter

E is disposed in its usual position beneath the manifold D and the discharge outlet of the carbureter is provided with a flange which ordinarily connects with the flange on the end of the manifold D. In the present 55 instance however, I have interposed a block 1 which is of the same shape as the flanges of the ends of the manifold and carbureter, the block having a central opening for establishing communication between the manifold and the discharge end of the carbureter. Within this opening in the spacing block 1 I have provided a filter constructed of suitable foraminous material and including the cylindrical portion 2 which has a conical extension 3 projecting into the discharge neck of the carbureter as shown to advantage in Figure 1 of the drawing. The spacing block 1 of the flanges on the manifold and carbureter are all bolted tightly together 60 through the medium of fastening bolts 4 extending through the flanges and through the spacing blocks. In one side of the block 1 I have provided a screw threaded opening 5 which communicates with the interior 65 of the block and receives a screw threaded nipple 6 connected to a valve 7 having a hand lever 8 by which the valve may be opened and closed. A flexible pipe or hose 9 is connected to the valve 7 through the 70 medium of a coupling 10 and the opposite end of the hose 9 is adapted to receive gases from the discharge pipe D of the manifold C. Surrounding the break which is provided in the discharge pipe D is a sleeve 11 75 forming a chamber 12. This sleeve as shown to advantage in Figure 4 is connected to the discharge pipe by clips 13 which extend around the pipe and are looped through openings in the marginal edge of 80 the sleeve 11. The end of the hose is extended through the sleeve and terminates within the chamber 12 so that the hot gases from the manifold are passed through the 85 pipe and through the valve 7 into the interior of the opening in the block 1.

In the nipple 5 I have extended one end of a cylindrical strainer 14 which projects transversely across the opening in the block, the cylindrical portion 2 of the filter having 90

an opening through which the strainer 14 projects.

Having thus described my invention, what I claim as new is:

- 5 An attachment of the character described comprising a block having a central opening therein, a filter arranged within the

opening and including a tapered conical portion depending from the block, and a tubular strainer projecting transversely 10 through the block and through the said filter.

In testimony whereof I affix my signature,

PAUL J. WEBER.
